AIR CONDITIONING APPARATUS

Joseph H. Reynolds, Cisco, Tex.

Application March 23, 1935, Serial No. 12,603

3 Claims. (Cl. 261—99)

This invention relates to new and useful improvements in air conditioning apparatuses.

One object of the invention is to provide an improved apparatus for conditioning air, which is particularly adaptable for use in restricted areas, such as rooms.

An important object of the invention is to provide an improved portable air conditioning apparatus including a plurality of moisture absorbing wicks, which are arranged to be maintained moistened at all times, whereby air passing through and around said wicks is cooled.

Another object of the invention is to provide an improved air conditioning apparatus comprising a plurality of moisture absorbing elements having their ends extending into water reservoirs, whereby the elements are kept saturated by capillary attraction.

A further object of the invention is to provide improved means for supporting moisture absorbing elements in an air conditioning apparatus, said means being so arranged as to permit the major portion of said elements to be exposed to the air while rigidly holding said elements in a desired position.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is an isometric view of an air conditioning apparatus constructed in accordance with the invention.

Figure 2 is a transverse, vertical sectional view of the same, showing the apparatus mounted on a support and having a fan for directing air there-through.

Figure 3 is a view, partly in elevation and partly in section, of the front of the apparatus.

Figure 4 is a transverse, vertical sectional view, taken on the line 4—4 of Figure 3, and

Figure 5 is a transverse, vertical sectional view of one of the couplings.

In the drawing the numeral 10 designates a casing or housing, which is substantially rectangular in shape and which may be constructed of sheet metal or other suitable material. The casing is provided with a hinged top 11, which is arranged to swing upwardly, as shown in dotted lines in Figure 2. The rear wall of the container is provided with a rectangular opening 12, while the front wall is provided with a similar opening

13, whereby air currents may freely pass through the casing.

For cooling this air passing through the casing, a pair of water tanks or reservoirs 14 and 15 are mounted within the casing. The tank 14 is located in the upper end of the casing, being supported on angle bars 16, which are welded or otherwise secured to the end walls of the casing within the same. It is pointed out that the bottom of the tank 14 is slightly above the upper edge of the openings 12 and 13, so that said tank will not interrupt the passage of air through the casing. The lower tank 15 is located in the bottom of the casing, as clearly shown in Figure 2, being welded or otherwise suitably secured therein. The top of this tank terminates short of the lower edge of the openings 12 and 13.

A plurality of moisture absorbent elements, such as cylindrical wicks 17, are disposed vertically within the casing between the tanks 14 and 15. The upper end portion of each wick is secured in a coupling 18 depending from the upper tank 14, while the lower end portion of each wick extends through and is secured to a coupling 19 located in the lower tank 15. The couplings 18 and 19 are substantially the same and, as clearly shown in Figure 5, each coupling comprises a metal collar 21, which is fastened in the tank and has its protruding end flared outwardly. In inserting and fastening the end portion of one of the wicks in the coupling, an expansible and compressible sleeve 22, preferably made of rubber or other resilient material, is slipped over the wick and frictionally engages the same. This sleeve with the wick therein is then compressed and inserted into the collar 21 and said sleeve is of a greater length than the collar, whereby one end of the sleeve extends beyond the protruding end of the collar. This extending end of the sleeve 22 is then turned back over the flared end 25 of the collar and this, together with the frictional engagement of the compressed sleeve in the collar, holds the wick in position. The couplings, depending from the upper tank 14, have their collars 21 elongated upwardly so as to terminate 30 near the top of the tank, while the collars of the lower tank are elongated downwardly (Figure 4), and it is obvious that when the wicks are fastened in the couplings, as has been described, the ends of said wicks extend beyond the inner ends of 35 the collars into the tanks. The tanks are filled with water, and due to end immersion and capillary attraction, the wicks are kept constantly 40 saturated. Therefore, air passing through the openings 12 and 13 in the casing must pass 45

50

55

through and around the saturated wicks because a sufficient number of wicks are provided to substantially extend across the length of the openings. Thus, it will be seen that this air passing through and around the wicks is cooled.

For supporting the wicks and retaining them in a vertical position, a spring coil 23 is provided for each wick. The upper end of each coil is secured to one of the couplings 18, while the lower end of the coil is secured to one of the couplings 19. The coils may be formed of any suitable material, but it is preferable to form them of wire which is rust proof and capable of considerable flexibility without losing the shape into which it is formed. The ends of the coils may be connected or attached to the couplings by welding or in any other suitable manner.

The coils are tensioned sufficiently to prevent sagging, but if desired all or part of the coils may be extended and thus compressed endwise when secured between the couplings. The coils are disposed side by side, or parallel, and each coil is spaced from those on each side thereof. It is obvious that the number of coils may vary. One of the wicks 17, which is made of moisture exuding material, such as felt fabric or the like, is inserted into each coil. The wicks are preferably of a smaller diameter than the interior of the coils so that when they are moistened and swell, they will not protrude between the turns of the coils or buckle between the couplings.

From the foregoing it is obvious that air passing through the openings 12 and 13 in the casing must pass through and around the wicks which are kept saturated by capillary attraction. The wicks serve to cool the air as it passes therethrough. If desired, adjustable louvers 24 may be mounted in the opening 13, whereby the amount of air passing through the casing may be readily controlled. It is pointed out that the coils are merely means for supporting the wicks to hold them in position, and any suitable bracing means may be employed.

Since the device is mounted in a single casing, it comprises a portable unit which may be readily moved from place to place. In Figure 2, I have shown the casing mounted forwardly of an electric fan 25, whereby a constant draft of air is forced through the casing. The fan is not an essential part of the apparatus, for the casing could be placed before an open window or in any other suitable place.

It is brought out that the arrangement of the unit is such that its action is entirely automatic. There are no adjustments to be made and all that is necessary is to occasionally fill the water tanks 14 and 15. The hinged top 11 provides for the easy removal and insertion of the upper tank 14, as well as the refilling thereof. The lower tank may be readily refilled through the opening 12 in the rear wall thereof. So long as the tanks contain water, capillary attraction will keep the wicks saturated and so long as the wicks are kept saturated, air passing through the casing will be cooled.

What I claim and desire to secure by Letters Patent, is:

1. An air conditioning device, comprising, a rectangular housing frame closed at the top and bottom and two opposite sides, said frame being open at front and rear for the passage of an air current therethrough, a rectangular tank fitted in the bottom portion of said housing frame with its top below the plane of the bottom edges of the front and rear openings, a similar tank fitted in the top portion of said housing frame with its bottom above the plane of the top of said openings, the bottom tank being apertured in its top wall and the top tank likewise having aligned apertures in its bottom wall, nipple tubes secured in the respective apertures with leak-tight fitting, the inner ends of said nipple tubes extended within the respective tanks and the outer ends thereof protruded and flared, and elongated wicks having sleeves of resilient compressible moisture-proof material slipped over their opposite end portions with the ends of the wicks extending beyond the respective sleeves, said sleeves being inserted under compression in opposed aligned nipple tubes of said top and bottom tanks.

2. An air conditioning device, comprising, a rectangular housing frame having front and rear openings for the passage of an air current therethrough, opposed tanks located in the housing frame on opposite sides of said openings, a series of spaced wicks disposed in parallel relation to each other across said openings, said tanks having aligned apertures in their opposed walls for the placement of the opposite end portions of the respective wicks within said tanks, each opening being provided with a nipple tube secured therein with leak-tight fitting and the end portions of said wicks having sleeves of resilient compressible moisture-proof material slipped thereover, the ends of the wicks extending beyond said sleeves and the sleeves being inserted under compression in the respective nipple tubes.

3. An air conditioning device, comprising, a rectangular housing frame having front and rear openings for the passage of an air current therethrough, opposed tanks located in the housing frame on opposite sides of said openings, a series of spaced wicks disposed in parallel relation to each other across said openings, said tanks having aligned apertures in their opposed walls for the placement of the opposite end portions of the respective wicks within said tanks, each opening being provided with a nipple tube secured therein with leak-tight fitting and the end portions of said wicks having sleeves of resilient compressible moisture-proof material slipped thereover, the ends of the wicks extending beyond said sleeves and the sleeves being inserted under compression in the respective nipple tubes, the adjacent end portions of said sleeves being extended beyond the outer ends of the nipple tubes and turned back thereover.

JOSEPH H. REYNOLDS.
